(57) **CLAIM**

The ornamental design for a combination of a door sensor and magnet, as shown and described.

DESCRIPTION

FIG. 1 is a front perspective view of a combination of a door sensor and magnet showing our new design;
FIG. 2 is a front perspective view of the combination of a door sensor and magnet in contact with each other thereof;
FIG. 3 is a front elevation view of the door sensor of the combination of a door sensor and magnet thereof;
FIG. 4 is a rear elevation view of the door sensor of the combination of a door sensor and magnet thereof;
FIG. 5 is a front elevation view of the magnet of the combination of a door sensor and magnet thereof;
FIG. 6 is a rear elevation view of the magnet of the combination of a door sensor and magnet thereof;
FIG. 7 is a left-side elevation view of the door sensor of the combination of a door sensor and magnet thereof;
FIG. 8 is a right-side elevation view of the door sensor of the combination of a door sensor and magnet thereof;
FIG. 9 is a left-side elevation view of the magnet of the combination of a door sensor and magnet thereof;
FIG. 10 is a right-side elevation view of the magnet of the combination of a door sensor and magnet thereof;
FIG. 11 is a top plan view of the door sensor of the combination of a door sensor and magnet thereof;
FIG. 12 is a rear plan view of the door sensor of the combination of a door sensor and magnet thereof;
FIG. 13 is a top plan view of the magnet of the combination of a door sensor and magnet thereof; and,
FIG. 14 is a rear plan view of the magnet of the combination of a door sensor and magnet thereof.
